UNITED STATES PATENT OFFICE.

AARON M. ADAMS AND MAXWELL W. LANDAU, OF PHILADELPHIA, PENNSYLVANIA.

HATBAND.

1,307,172.

Specification of Letters Patent. Patented June 17, 1919.

Application filed October 6, 1917, Serial No. 195,101. Renewed December 4, 1918. Serial No. 265,258.

To all whom it may concern:

Be it known that we, AARON M. ADAMS and MAXWELL W. LANDAU, citizens of the United States, residing at 2102 N. 9th St., Philadelphia, in the county of Philadelphia and State of Pennsylvania, have invented new and useful Improvements in Hatbands, of which the following is a specification.

This invention relates to a combined head grip and ventilating hat band, and has particular application to a device of the class described which may be readily and quickly applied to, what is commonly termed, the sweat band of any hat.

In carrying out the present invention, it is our purpose to provide a device of the type set forth which will be constructed in such manner as to enable the hat to be ventilated, and which will cause the hat band to conform to the shape of the head of the wearer, thereby enabling the hat to be worn with comfort.

It is also our purpose to provide a combined head grip and ventilating hat band which will be so associated with the hat as to form a cushion between the hat and the head, thereby avoiding discomfort to the wearer.

Another object of the invention is the provision of a combined head grip and ventilating hat band which will be constructed in such manner as to absorb perspiration, thereby eliminating the discoloring of the hat band and preventing the perspiration from penetrating to the outer surface of the hat.

With the above cited objects and others of a similar nature, the invention consists in construction, combination and arrangement of parts set forth in the following description and falling within the scope of the appended claims.

In the accompanying drawing—

Figure 1 is a fragmentary sectional view of a hat equipped with a combined head grip and ventilating hat band constructed in accordance with our invention.

Fig. 2 is a fragmentary bottom plan view of the same.

Fig. 3 is a fragmentary sectional view through the head grip and hat band.

Fig. 4 is a similar view showing the parts enlarged.

Referring now to the drawing in detail,

1 designates a portion of a hat which, in 55 the present instance, is of a straw variety, while 2 indicates my combined head grip and ventilating hat band arranged within the hat in the usual place. The hat band 2 is composed of leather or other desired material and, adjacent to its outer edge, is formed with an annular row of perforations 3 which extend entirely around the band. Arranged upon the surface of the hat band 2 next adjacent to the inner side of the hat 65 1 and disposed contiguous to the outer edge of the hat band, is a tape 4 composed of cloth or other fabric capable of absorbing perspiration. This tape 4 overlies the annular row of perforations 3 and, in the present instance, is folded upon itself circumferentially to provide a pocket 5, and has one edge curled upon itself, in a direction opposite to the fold, to provide a loop 6. The loop 6 is arranged within the edge of the 75 hat band and contiguous thereto, in order to receive the stitches that secure the hat band to the hat, as hereinafter described. The side edges of the tape 4 are disposed in the same relative positions at opposite sides 80 of the pocket, and these edges are stitched to the corresponding edge of the hat band, as at 7. Extending through the pocket 5 is an elastic band or strip 8, while arranged within the loop 6 and extending entirely 85 around such loop, is a reed 9. In the present instance the tape 4 is split or cut transversely at the back end of the hat and the ends of the elastic strip 8 project beyond the corresponding ends of the tape 90 and overlap each other, as clearly illustrated in Fig. 3 of the drawing, these overlapping ends being secured together by a suitable fastening device, as the clasp 10. The looped portion 6 of the tape 4 is stitched to 95 the inner surface of the hat at the juncture of the crown with the brim, the stitches encircling the reed 9, as clearly shown in Fig. 4, so that head grip and hat band will be fastened to the hat as a unit.

In practice, the elastic strip 8 acts normally to contact the hat band 2, and holds the band 2 spaced apart from the body of the hat, as illustrated in Fig. 1. When the hat is placed upon the head of the wearer 105 the strip 8 yields or gives and causes the band to conform to the shape of the head, and to snugly fit the same, while owing to

the space between the hat band and the body of the hat, a cushion is formed which enables the hat to be worn with comfort. The perspiration is absorbed by the tape 4 5 through the perforations 3 in the hat band.

Another very important feature of the invention resides in the fact that the elastic strip 8 tends to prevent the lower edge of the hat band at the forward end of the hat, 10 from creeping out of the hat, incident to the continued putting on and taking off of the hat.

While we have herein shown and described one preferred form of our invention 15 by way of illustration, we wish it to be understood that we do not limit or confine ourselves to the precise details of construction herein shown and described, that modification and variation may be made within 20 the scope of the claims and without departing from the spirit of the invention.

We claim:

1. In a combined head grip and ventilating hat band, a hat band having the outer 25 edge perforated, a tape secured to the side of said band next adjacent to the hat and covering said perforations to absorb the perspiration, and formed to provide a circumferentially extending pocket, and an 30 elastic strip within the pocket acting to con-

tract said tape and hat band to fit the latter to the head of the wearer.

2. In a combined head grip and ventilating hat band, a hat band having the outer edge perforated, a tape secured to the side 35 of said band next adjacent to the hat and covering said perforations to absorb the perspiration, and formed to provide a circumferentially extending pocket, an elastic strip within the pocket acting to contract 40 said tape and hat band to fit the latter to the head of the wearer, said tape being also formed to provide a loop arranged within the edge of said hat band, and a reed within said loop adapted to be encircled by the 45 stitches that connect the hat band to the hat.

3. In a combined head grip and ventilating hat band, a hat band having the outer edge perforated, a tape secured to the side 50 of said band next adjacent to the hat and covering said perforations to absorb the perspiration, and an elastic band secured to said tape and acting to contract the tape and hat band to fit the latter to the head of the wearer.

In testimony whereof we affix our signatures.

AARON M. ADAMS.
MAXWELL W. LANDAU.
